ROTARY INTERNAL COMBUSTION ENGINE

Frank David Butler, United States Navy

Application May 16, 1938, Serial No. 206,218

7 Claims. (Cl. 244—54)

(Granted under the act of March 3, 1883, as
amended April 30, 1928; 370 O. G. 757)

My present invention relates to rotary internal combustion engines, more particularly of the two stroke cycle type, wherein such engines are used to rotate an impeller or propeller. I have found that ordinarily the majority of such engines are mounted so as to operate other than with the cylinders thereof forming an integral part of such impeller or propeller, and thus not accomplishing certain efficiencies that can be obtained in this combination of units. Furthermore, the majority of this type of engines are not normally attached to or mounted in the objects which they impel or propel in such a manner so that they may be conveniently removed from or reinstalled in such objects, nor in such a manner that the maximum efficiency in steering, elevating or depressing of such objects can be attained.

The solution of these major problems, in addition to the complete accomplishment of their many minor resulting problems, have been long and vainly sought by many in this art.

The major concept of my present invention is the complete solution of these problems by the provision of a simple, durable, efficient and relatively inexpensive engine and impeller or propeller unit assembly combination and mounting means, for its practical and commercial accomplishment.

More specific concepts of my invention contemplate—(a) the provision of constructing such engine and impeller or propeller so that the cylinders of such engine will be integral with and will revolve with such impeller or propeller; (b) the provision of mounting such combined engine and impeller or propeller unit, in the objects which they impel or propel, in such a manner that they may be conveniently removed from or reinstalled in such object as a single unit assembly, such mounting to be made preferably in a ball and socket manner so that the axis of such combined unit may be shifted to various angles to the centerline of such object during the period such engine is in operation, and the further provision of means for accomplishing such shifting of such combined unit; (c) the provision of means for preventing the crank shaft of such engine from rotating within the ball of such ball and socket means; (d) the provision of means for preventing such ball from rotating within its socket with the moving elements of such engine and to still allow freedom for the oscillation of such ball in its socket; (e) the provision of a locking device means for securing such ball within its socket in a fixed position combined with means for varying the tension on such locking

device hydraulically and remotely; (f) the provision of means for attaching the engine fuel and lubricating oil supply means to the ball socket mentioned and for accomplishing inlet supply to such engine through the ball of such socket; (g) the provision of valve means for timing the inlet supply (mentioned under provision (f)) wherein the rotary hub like journal of the engine combined cylinder and impeller or propeller unit times the period of such inlet supply through such ball and socket assembly mentioned; (h) the provision of a further valve means for timing such inlet supply wherein a suitable port in one of the main journals of the crank shaft of such engine cooperates with a plurality of radial ports, in the rotary hub like journal mentioned, during the rotation of the latter and thus further controls the timing period of such inlet supply; (i) the provision of electrical ignition means for such engine; (j) the provision of efficient means for cooling the cylinders of such a combined engine unit by stream-lining the cooling fins of such cylinders parallel to the faces of the impeller or propeller blades; (k) the provision of means in such a combined engine unit for utilizing the exhaust gas of such engine to assist in the rotation of such impeller or propeller of such unit; (l) the provision of means for muffling the sound of such exhaust gas escaping from the cylinders of such engine; (m) the provision of means for securing a telescope, an automatic gyro steering or altitude control apparatus, or a machine gun in such a manner that they will be shifted as if integral with such ball of such ball and socket mentioned; (n) the provision of means, in the form of a cam mounted on the end of the rotary hub like journal mentioned and for the purpose of timing the firing of such machine gun mentioned in relation to the rotation position of travel of the blades of such impeller or propeller; and (o) the provision of means comprising the combination of the foregoing provisions and other minor new and useful entities which practically, commercially, efficiently and economically practice, in the form and manner found by me thus far in the development of my invention to be most advantageous in each of the foregoing, as a whole, and such other respects as will more clearly appear, and be understood by those skilled in this art, from the accompanying drawings and the following description, and the appended claims.

It will be readily appreciated by those skilled in this art, after understanding my invention, that various changes may be made in the means disclosed herein which will produce the same result.

sults in substantially the same manner without digressing from my invention concept or sacrificing any of its outstanding inherent advantages.

With reference to the drawings:

5 Fig. 1 is a vertical, longitudinal section through an engine, impeller and ball and socket assembly combined in one unit assembly as per my invention and mounted in the nose of a small aviation plane, such section being as would appear on the 10 dotted line 1—1 of Fig. 6.

Fig. 2 is a transverse section through the center of the ball and socket assembly, as would appear on the dotted line 2—2 of Fig. 1, and illustrates the relation in position of the inlet supply ports to one another when the moving elements of the engine are in the position they occupy in Fig. 1. The small arrow below the figure diagrammatically illustrating the position of and direction of rotation of the lower blade of the 20 impeller of Fig. 1.

Fig. 3 is similar to Fig. 2 except illustrating the relation in position of the inlet supply ports to one another at the commencement of admission and with the moving elements of the engine in 25 the position they would occupy when the lower blade of the impeller of Fig. 1 had reached the position diagrammatically illustrated by the small arrow.

Fig. 4 is similar to Figs. 2 and 3, except illustrating the relation in position of the inlet supply ports to one another at the completion of the admission period of operation of the engine and with the moving elements of the latter, in the 30 position of travel they would occupy when the lower blade of the impeller of Fig. 1 had reached the position diagrammatically illustrated by the small arrow (approximately 225 degrees from its position in Fig. 1).

Fig. 5 is a section of a portion of the ball and 40 socket assembly and illustrates the variable tension, fixed location, locking device for the ball of such assembly, such device being hydraulically controlled remotely from such assembly.

Fig. 6 is a transverse section through the center of the engine and impeller as would appear 45 on the dotted line 6—6 of Fig. 1, and illustrates the compactness of this type combined assembly.

Fig. 7 is a transverse section through the upper 50 blade and cylinder of Fig. 6 as would appear on the dotted line 7—7 of that figure. This section illustrates the exhaust gas passages and the piston by-pass supply ports.

Fig. 8 is partly a plan view and partly a transverse section of and through the upper blade and 55 cylinder of Fig. 6 as would appear on the dotted line 8—8 of that figure. This figure illustrates the stream-lining of the cylinder air cooling fins with the blade angle and the unique location, enclosure and stream-lining of one of the ignition 60 plugs.

Fig. 9 is a diagrammatic sketch illustrating the installation of my invention in an aviation plane. This sketch illustrates the general location of the engine ball and socket mounting 65 assembly and the shifting lever of such ball.

In the accompanying drawings, similar numerals and letters indicate similar parts in the several views, the numeral 1 indicates the two throw crank shaft which is adapted to be suitably journaled in the forward and rear main 70 bearings 2 and 3 respectively, which are a tight fit in the crank case end covers. Secured to the forward end thereof is the high tension magneto 4 magnet wheel, and toward the rear end thereof is secured the locking collar 5. The rear

end of crank shaft 1 is elongated and has secured thereto at the end thereof the combined engine counterweight and maneuvering handle grip 1a. The intermediate portion of the elongated shaft 1 has secured thereto the gun clamping bracket 1b, the crank shaft 1 not being rotatable but held stationary by the locking collar 5.

The blades 6 of the impeller are preferably die forgings of steel alloy and are constructed as light in weight as is possible consistent with the necessary strength.

The blades are integral with engine cylinders 6a and halves of crank case 6b and are adapted to rotate around the engine crank shaft 1. Cylinder exhaust ports or passages 6c are located in and extend through the walls of the cylinders 6a in such a location that the exhaust gas passing therethrough will have a reactionary effect tending to assist in the rotation of the blades 6 in a forward direction of travel. Also integral with the blades and cylinders are cylinder supply or piston by-pass ports 6d forming by-pass communication between the crank case 6b and the cylinders 6a above the pistons when the latter are at or near the inward ends of their strokes. The spark plug recesses 6e are located in the lee of the cylinders 6a and the rear edge of the blades 6 so as to be streamlined and thus reduce air flow friction. Streamlined cylinder cooling fins 6f are located parallel to the blades 6 and are constructed so as not to restrict the air flow past the cylinders and blades.

Pistons 7, manufactured of aluminum alloy, are adapted to reciprocate within the cylinders 6a and are fitted with resilient rings 7a, forming a seal between the pistons and the cylinder walls, and with deflection flanges 7b directing the inlet supply charge toward the outward end of the cylinder 6a and the expended exhaust gas toward the exhaust passages 6c. Connecting rods 8, manufactured of bronze or some heat treated steel alloy, are of the off-set type and connect pistons 7 with their respective crank throw journals of the crank shaft 1. The rods 8 are fitted at their outward ends with suitable piston pins 8a and at their inward ends with the bearing caps 8b, and are drilled lengthwise for lubricating purposes.

The crank case 6b, constructed as small as is possible in order to obtain a high inward travel piston compression ratio, is closed at the ends with flanged hub shaped covers 9 and 10 which are recessed in their flanged portions so as to coincide with the annular shaped end shoulders of the halves of the crank case 6b for the purpose of retaining the latter securely in contact with each other. These covers 9 and 10 are secured to the crank case with bolts 11. The crank case halves are also secured together by bolts 11a.

The forward cover 9 is an aluminum alloy casting which is adapted to support the magneto coil 4a and other stationary parts of such magneto and is counter-balanced at 9a with such parts. The rear cover 10 forms the main journal hub on which the crank case, cylinders and blades mentioned rotate. This cover 10 is manufactured of metal having considerable strength consistent with lightness of weight, it is drilled diagonally forming the diagonal supply ports 13g, it is drilled 71 or slotted radially forming the radial supply ports 13f and 13d, it is threaded on its outer diameter near its after end and it is fitted with its securing nut 10b and washer 10c. The after portion of cover 10 is cylindrical in shape and is ma-

chined externally to fit its journal roller bearings 10a and the inner diameter of its spherical shaped mounting ball 15. At its end, the cover 10 is fitted with a gun timing cam 14. The internal diameter of practically the entire length of cover 10 is bored and machined to receive the crank shaft after main bearing 3. The bulk portion of covers 9 and 10, crank case 6b, magneto 4, including the wiring conduits 4b of the latter, and such other parts as are in the immediate vicinity of the crank case 6b, are all enclosed within the streamlined, weather-tight, metal casings 16 which are secured to the crank case by the screws 16a. The high tension ignition wires 15 are enclosed between the magneto coil 4a and the spark plug recesses 6e in metal conduits 4b, and the spark plug recesses 6e are made water tight by the fibre caps 4d screwed onto the ends of spark plugs 4c and fitted tightly against the 20 ends of the recesses.

The spherical shaped combined engine and propeller mounting ball 15 is a casting and is machined externally to fit snugly within the internal diameter of the forward and rear 25 halves of the ball socket 15a and 15b respectively. The rear half of the socket is preferably secured in the nose of the plane fuselage and the forward half is secured to the after half with the bolts 18c, these halves being adjustable to the ball by 30 removing or replacing adjustment shims 15d. This ball 15 has a cylindrical shaped internal surface extending throughout its entire width, which surface is machined to receive the roller bearings 10a and the cylindrically shaped after 35 portion of the hub shaped crank case cover 10, and is slotted at the after end to receive and be keyed to the crank shaft locking collar or coupling 5. The ball 15 is further machined on its external diameter by being slotted at 15f for a short 40 distance parallel to the center line of the crank shaft to receive its securing key 15e. This key 15e has an elongated rectangular portion which fits snugly within this slot 15f and a cylindrically shaped portion which fits snugly within a suitable recess in the halves of the ball socket 15a 45 and 15b and prevents ball 15 from rotating in the socket without interfering with its oscillation therein. At any angle other than 90 degrees from parallel with the side surfaces of slot 15f, the ball 50 15 has machined in the external surface thereof a semi-circular recess 15g which is adapted to receive the ball bearing 17a of the variable tension locking device 17, described later, and has machined in the vicinity of the bottom center 55 thereof and extending through to its internal diameter the inlet supply passage 13c, and in the upper half it is equipped with the grease ports 15h which connect the grease plug fitting 15i with the roller bearings 10a, ball securing key 15e with its slot 15f and the outer circumference of such ball. In fact, the whole cored out section of ball 60 15 may be packed with grease and connected so as to lubricate the parts mentioned that are to be greased.

The after half 15b of the ball socket has secured to the lower central after portion thereof with bolts 18v the mixing valve or carburetor 13, and has a horizontal cylindrically shaped cored or machined passage 13b extending therethrough 65 and connecting the carburetor 13 with the radial inlet passage 13c in the ball 15.

The variable tension locking device 17 is secured preferably to the half 15b of the ball socket halves and coincides with recess 15g of the ball 70 15, and consists of a ball bearing 17a fitting in

recess 15g, a combined ball cup and spring retainer member 17b, a resilient coil spring 17c, a combined spring retainer and piston member 17d, which latter has secured thereto the leather cup 17e and its securing washer 17f, all of the foregoing parts fitting snugly within a suitable cylindrical chamber 17g which is open at the ball end and reduced at the opposite end of the body portion 17, and is connected at the latter end through the connection and tubing 17h to a common screw compression type grease cup, not illustrated, located remotely from 17. With reference to Fig. 5 and assuming that the grease cup mentioned and tubing 17h is filled with medium body grease, any supply of such grease from such grease cup to the right of 17e in 17g would increase the tension of spring 17c on ball bearing 17a and consequently on ball 15, and vice versa, while an abnormal supply of grease to 17g would cause the adjoining ends of members 17b and 17d to 20 contact and thereby result in locking ball 15 with ball bearing 17a. This locking device 17 is designed to remotely and hydraulically lock or vary the tension of the locking of ball 15 in a fixed position in its socket through the manual efforts 25 of the engine operator. The oscillation of the ball in its socket, and consequently the shifting of the angle of the impeller 6 to its ball socket mounting, is accomplished manually in small engines by the operator through the handle 30 grip 1a.

As customary in two stroke cycle engines the engine lubricating oil is mixed with the gasoline and is supplied to the engine along with the inlet supply charges through the carburetor 13, which 35 is equipped with the usual common type butterfly control valve 13w, needle valve 13x, float chamber 13y, and gasoline connection 13z. The inlet fuel supply charge to the cylinders 6a from the atmosphere through the opening in the bottom of the triple screened air filter 13a is accomplished as follows:

As the impeller blades 6 are rotated to the right, Fig. 6, the pistons 7 are moved outward in their respective cylinder 6a, due to the fact 45 that the crank shaft does not rotate, from the position in which they are illustrated in Figs. 1 and 6. This outward movement of pistons 7 causes them to cover the cylinder supply ports 6d, and the rotation of the propeller also causes the 50 cylindrically shaped portion of the hub journal 10 to rotate within the ball 15 from the position in which it is illustrated in Fig. 2 to the position in which it is illustrated in Fig. 3 and in the direction of travel illustrated by the small arrows in 55 both figures.

At approximately the instant that the pistons cover the outer ends of ports 6d, the radial supply ports 13f and 13d in hub journal 10 and bearing 3 start cooperation with the longitudinal supply port 13e, located in the crank shaft 1 and extending longitudinally therein between the ports 13d and 13f. The port 13d at this same instant starts cooperation with the radial supply passage 13c in the ball 15. As the pistons 7 continue their 65 outward travel in cylinders 6a a partial vacuum is formed in the crank case 6b and causes air to be drawn from the outside atmosphere through the strainer 13a, thence through the carburetor 13 where it mixes with the gasoline and lubricating 70 oil, thence through the horizontal supply passage 13b, thence through the radial supply passage 13c, thence through the radial supply port 13d, thence through the horizontal supply passage 13e, thence through the radial supply port 13f, which is in 75

constant communication with the diagonal supply ports 13g, and thence through the diagonal supply ports 13g into the crank case 6b. This supply suction continues during the remainder of the outward travel of the pistons 7 and somewhat beyond the outward dead center stroke travel of such pistons, due to the generated velocity of travel of the inlet supply charge, as diagrammatically illustrated by the position of travel of the power blade 6 of Figs. 1 and 6 by the small arrow in Fig. 4. At this point of travel of the pistons 7 as illustrated by the position of travel of the hub 10, Fig. 4, the inlet supply port 13d cuts off its cooperation with inlet supply passages 13c and 13e, while at the same instant supply port 13f cuts off its communication cooperation with inlet supply passage 13e, and thus the inlet supply to the crank case 6b is terminated.

As the pistons 7 travel inward from their outward dead centers, the inlet supply charge in the crank case 6b inward of them is compressed in the crank case, being trapped, without an outlet from crank case 6b, the amount of compression pressure attainable within such crank case depending upon the piston displacement compression ratio.

As the pistons 7 near the inward ends of their inward dead centers, they uncover the cylinder supply ports or piston by-pass ports 6d and allow the compressed inlet supply charge in the crank case 6b to flow through the ports 6d into the cylinders 6a and there to be deflected toward the ends of such cylinders by the deflection flanges 7b of the pistons 7. As the pistons 7 continue their travel and start outward in their respective cylinders 6a, the combustion supply charge is compressed in the cylinders outward of the pistons 7 and as the pistons near their outward dead centers a spark from the high tension magneto 4 occurs at the spark plugs 4c and combustion of the fuel supply charge follows, thus forcing the pistons 7 inward on their power strokes. As the pistons near their inward dead centers of travel they uncover the exhaust ports or passages 6c and the expanded gas is allowed to escape into the atmosphere. As this exhaust gas leaves the cylinders under considerable absolute pressure, its velocity is somewhat higher than the rotary speed of the cylinders at the radius from the center of the crank shaft at which passages 6c are located, and consequently a reactionary effect results, and as the exhaust passages are a part of and are located in the lee of the rotary motion of the impeller blades 6, the blades are kicked ahead in a forward motion by such reactionary effect. It is obvious, therefore, that inasmuch as the velocity of the exhaust gas leaving the cylinders in the manner described is reduced by the feet per second travel of the cylinders in an opposite direction, that the sound caused by such exhaust would be muffled considerably. The sound would also be further muffled by the air passing through the silencer holes 6g, which latter are located in the sides of exhaust ports 6c.

The cylinder supply or piston by-pass ports 6d are drilled diagonally to the walls of the cylinders 6a, as illustrated in Fig. 6, so that the inlet supply charge as it passes from the crank case 6b to the cylinders 6a will be scooped from the crank case due to the direction of rotation and velocity of travel of impeller 6 and will enter the cylinders at an angle and under a velocity such that will force it toward the outer ends of such cylinders and will cause it to displace the exhaust gas therein. The inner ends of these supply ports 6d have pressed thereinto the annular shaped lubricating oil baf-

fles 6h which project slightly into the crank case 6b and thus prevent centrifugal force from throwing the bulk of the lubricating oil from the crank case into the cylinders 6a through ports 6d.

The inlet supply to crank case 6b is considerably accelerated due to the velocity of rotation travel of the hub shaped cover 10 and the centrifugal force generated during such rotation.

It is also understood that the gasoline type of engine herein shown may be replaced by an oil fuel powered engine of the compression ignition type.

When this engine assembly is used in a small plane for military purposes, a machine gun 14a may be clamped in a pair of brackets similar to 14b which will cause the gun to be moved with the shaft 1b and to point in the direction which the impeller is pulling the plane as diagrammatically illustrated in Fig. 1 and on the object being pursued. In such a case the handle grip weight 14a can be eliminated and the ball 15 oscillated with the butt-stock of the gun. The firing mechanism of the gun can then be connected up electrically so that said gun may be fired either by closing or opening the electric circuit by and through cam 14 which latter is in timing with the impeller blades.

It is further contemplated that a plane of approximately eight foot wing spread, adapted to carry the operator only, and equipped with a relatively small engine, impeller and ball and socket mounting assembly of the type described herein, could be built so as to take off and land having little or no run-way, so as to make approximately 250 miles per hour, and have a flight radius of 1,000 miles or more.

With the type of combined engine and impeller as herein described mounted in bearings to rotate in a ball and socket of the type specified and with the latter mounted in the nose of an aviation plane, it is obvious that such plane could be steered, elevated or depressed by changing the angle of said combined engine and impeller to said nose of said plane through movement of said ball, and that the usual rudder, elevator and aileron controlling devices (if and if installed and used in such plane) would be for abnormal purposes only in controlling the movement of such plane.

It is apparent that if any one organization were to operate a fleet of planes, boats or rapid transit vehicles powered with assemblies as described herein, that such planes, boats or vehicles could be quickly restored to service in case of damage to such assembly by and through replacing such damaged assembly minus half of ball socket 15b with a spare assembly.

While starting the engine and operating it under steady cruising conditions the ball 15 may be locked in its central position in its socket by the fixed position locking device 17.

The invention herein described may be manufactured and used by or for the Government of the United States of America for governmental purposes without the payment to me of any royalty thereon or therefor.

Having fully described my invention, what I claim as new and desire to secure by Letters Patent is:

1. In an internal combustion engine having a non-rotatable crank shaft and a plurality of cylinders extending radially therefrom and rotatable concentrically thereto, an elongated tubular hub member secured to and extending an appreciable distance at right angles from said

5. In an internal combustion engine having a non-rotatable crank shaft and a plurality of cylinders extending radially therefrom and rotatable concentrically thereto, an elongated tubular hub member secured to and extending an appreciable distance at right angles from said cylinders and concentric with said crank shaft, said hub member being rotatably journaled on said crank shaft, a spherical ball member within which said hub member is rotatably journaled, 10 and a spherical ball socket within which said ball member is oscillatably journaled, said engine rotating said hub member internal to said ball member and external to the surface of said crank shaft, and means for oscillating said ball member within said ball socket. 15
2. In an internal combustion engine having a non-rotatable crank shaft and a plurality of cylinders extending radially therefrom and rotatable concentrically thereto, an elongated tubular hub member secured to and extending an appreciable distance at right angles from said cylinders and concentric with said crank shaft, said hub member being rotatably journaled on said crank shaft, a spherical ball member within which said hub member is rotatably journaled, 20 and a spherical ball socket within which said ball member is oscillatably journaled, said engine rotating said hub member internal to said ball member and external to the surface of said crank shaft, means for oscillating said ball member within said ball socket, and means for preventing said ball member from rotating within said ball socket comprising a key extending from the body portion of said ball socket into an elongated circumferentially extending keyway located in the periphery of said ball member parallel to said crank shaft of the engine. 25
3. In an internal combustion engine having a non-rotatable crank shaft and a plurality of cylinders extending radially therefrom and rotatable concentrically thereto, an elongated tubular hub member secured to and extending an appreciable distance at right angles from said cylinders and concentric with said crank shaft, said hub member being rotatably journaled on said crank shaft, a spherical ball member within which said hub member is rotatably journaled, and a spherical ball socket within which said ball member is oscillatably journaled, said engine rotating said hub member internal to said ball member and external to the surface of said crank shaft, means for oscillating said ball member within said ball socket, and means for preventing said crank shaft from rotating within said ball member comprising an annular shaped disc secured to said crank shaft and said ball member and located within the latter. 35
4. In an internal combustion engine having a non-rotatable crank shaft and a plurality of cylinders extending radially therefrom and rotatable concentrically thereto, an elongated tubular hub member secured to and extending an appreciable distance at right angles from said cylinders and concentric with said crank shaft, said hub member being rotatably journaled on said crank shaft, a spherical ball member within which said hub member is rotatably journaled, and a spherical ball socket within which said ball member is oscillatably journaled, said engine rotating said hub member internal to said ball member and external to the surface of said crank shaft, means for oscillating said ball member within said ball socket, and means for controlling means for locking said ball member within said ball socket in a predetermined fixed position comprising a hydraulically operated remote- 40
5. In an internal combustion engine having a non-rotatable crank shaft and a plurality of cylinders extending radially therefrom and rotatable concentrically thereto, an elongated tubular hub member secured to and extending an appreciable distance at right angles from said cylinders and concentric with said crank shaft, said hub member being rotatably journaled on said crank shaft, a spherical ball member within which said hub member is rotatably journaled, 45 and a spherical ball socket within which said ball member is oscillatably journaled, said engine rotating said hub member internal to said ball member and external to the surface of said crank shaft, means for oscillating said ball member within said ball socket, access communication means for admitting an inlet charge to said engine consisting of a carburetor secured to the body portion of said spherical ball socket, a chamber extending from said carburetor through said body portion of and into the interior of said ball socket and providing constant communication therebetween, a radially extending cavity in said ball member providing constant communication between the interior and exterior of the latter and providing constant communication with said chamber, a radially extending port in said hub member providing constant communication between the interior and exterior of the latter and, during the rotation of said hub member within said ball member, coinciding and intermittently and simultaneously cooperating with and providing communication between said cavity in said ball member and a longitudinally extending passage in said crank shaft, said passage being located in the periphery of said crank shaft and extending longitudinally therein from the vicinity of said radially extending port an appreciable distance therebeyond toward said engine, a combined radially and diagonally outward extending passage located in said hub member and extending from the interior of the latter to the vicinity of the ends of the cylinders adjoining said crank shaft and, during the rotation of said hub member within said ball member, coinciding and intermittently cooperating with the engine end of said passage in said crank shaft. 55
6. In an internal combustion engine adapted to propel an object and having a non-rotatable crank shaft and a plurality of cylinders rotatable radially thereto, an elongated tubular hub member secured to and extending an appreciable distance at right angles from said cylinders concentric with said crank shaft, a spherical ball member having a cylindrically shaped chamber therein and having said hub member rotatably journaled therein, and a spherical ball socket secured to said object, said ball member being oscillatably journaled within said ball socket, said hub member being rotated by the engine. 60
7. In an internal combustion engine adapted to propel an object by and through a bladed propeller, a spherical ball socket secured to said object adjoining the engine, a spherical ball oscillatably journaled in said ball socket, means for attaching the engine to said spherical ball, means for preventing said ball from rotating within said ball socket, and means for oscillating said ball in said ball socket. 65

FRANK DAVID BUTLER.
